UNITED STATES PATENT OFFICE.

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

NAILING MACHINE.

Application filed December 11, 1925. Serial No. 74,753.

This invention relates to nailing machines and is herein exemplified in a machine for nailing heels upon shoes, although the field of utility of the invention is not limited to 5 machines for performing this particular nailing operation.

In the copending application of Joseph H. Pope, Serial No. 612,254, filed January 12, 1923, there is disclosed and claimed an 10 improved nailing die which actual use in shoe manufacture has shown to possess marked advantages over devices formerly used for similar purposes. It is the object of the present invention further to develop 15 the invention of the said application, with a view to increasing the facility with which a nailing machine in which it is incorporated may be accommodated to work of different sizes or work requiring different nailings.

For the accomplishment of the above stated object the invention provides, in combination with a gang of nail drivers the nail engaging ends of which are movable 20 into a plurality of different nailing patterns, a carrier provided with a plurality of different, nail driver controlling, pattern elements and movable, independently of the nail drivers, to place any selected one of pattern elements in co-operative relation to the drivers. By incorporating a series of 25 driver controlling pattern elements in the organization of the machine and making provision for their ready and selective interchangeability the change in the setting of the machine necessary to change it from one nailing to another is made possible of accomplishment in a few seconds, a period of time so brief as to have practically no retarding effect upon the production of work 30 by the machine.

In the illustrative embodiment of the invention herein shown, the movable carrier consists of a rotary turret in which the 35 driver guiding pattern elements are formed or mounted, the axis of rotation of the said turret being so located that any one of the pattern members, each of which is shown as comprising a set of guide holes, may be 40 readily moved into guiding relation to the nail drivers.

Preferably, there is combined with each 45 pattern element a heel holder so constructed and related to the pattern element as to locate and hold a heel having nail holes ar-

ranged according to the pattern element in proper relation to said element to cause the drivers to coincide with the nail holes in the heel. It thus becomes necessary for the operator, in changing from one heel nailing to another, merely to move the turret to the position to bring the proper pattern element and heel holder into co-operative relation to the nail drivers.

Further details of the invention and the advantages derived from its use will be understood and appreciated from reading the following detailed description of one practical embodiment thereof, in connection with the accompanying drawings; in which—

Figure 1 is a view, in front elevation, of a portion of a heel attaching machine embodying the invention;

Fig. 2 is a vertical section on the line II, II of Fig. 1; and

Fig. 3 is a plan view of the mechanism shown in Figs. 1 and 2.

Referring now to the drawings, 10 indicates a die block having projecting tongues 12 at its sides by which it is supported in the guides provided for that purpose in the frame 14 of a heelng machine which may be of the same general type of construction as that disclosed in the prior patent to J. H. Pope, No. 1,431,980, dated October 17, 1922, to which reference may be had for a more complete disclosure of the details of the heelng machine structure which are not illustrated in the present drawings.

The die block is chambered to provide an 90 open space 16 extending entirely through it and a group of driver guiding tubes 18, supported by ball and socket mountings 20 is located within the space 16. The mountings of the guide tubes 18 are arranged to 95 register with the nail drivers 22 so that when the drivers are lowered each driver shall enter its corresponding guide.

The mountings 20 of the guides 18 permit the nozzle ends of the guides to be swung 100 into various positions, to produce different nailing patterns, and the drivers 22 are sufficiently resilient to follow the deflected guides easily. The construction so far described is, or may be, substantially like that 105 disclosed in the Pope application identified above.

In order to control the movement of the drivers into different predetermined nailing patterns, a plurality of different pat-

tern elements 24 are provided. As shown, each of these pattern elements comprises a plate 26 provided with a series of tapered holes 28, the centers of which are arranged in the pattern of a desired nailling. It will be understood that the nozzle ends of the guide tubes 18, entering the holes 28, are thereby positioned in accordance with the nailling pattern which it is desired to produce.

The pattern plates 26 are mounted in, and may or may not be integral with, a turret 30 which is easily retatable about a journal 32, the axis of which is vertical. The upper end of the journal 32 is non-circular, as shown at 34, and is supported to slide vertically in a stationary bearing 36, a flange 38 at the upper end of the non-circular section 34 serving to limit downward movement of the journal by engaging the top of the bearing.

The turret 30 is provided with a sleeve 40 which fits rotatably upon the journal 32 and a nut 42, threaded upon the lower end of the journal, retains the turret thereon. A pin 44, threaded through the stationary bearing 36 and projecting in the path of rotation of the turret, is arranged to enter any one of a series of holes 46 in the upper face of the turret. There is one hole 46 for each pattern member 24 and the holes and pattern members are so related that when the turret is locked in a given position by the pin 44 engaging in a hole the corresponding pattern member is definitely located in nailling position, as may be clearly seen from Fig. 2. The turret 30 may be lowered, to disengage it from the locking pin 44, and for this purpose the journal 32 is provided with a depending portion 48 in which is mounted a pin 50. The pin 50 is engaged by the forked end of a lever arm 52 movable about a stationary pivot 54 by means of a handle 56. A spring 58, acting upon the handle 56, tends to keep the turret elevated, in engagement with the locking pin 44 but when the handle 56 is drawn outward the turret is depressed, disengaged from the locking pin, and may be easily rotated to place any selected one of the pattern members 26 in driver controlling position, whereupon the handle is released, allowing the turret to rise and be locked by the pin 44.

Secured to the under side of each pattern element 26 is a heel holder 60 arranged to locate and hold a heel having nail holes arranged to correspond to the holes 28 in said pattern element. In Fig. 2 a rubber heel 62 is shown in one of the heel holders 60, with a shoe 64 to which the heel is to be attached supported on a jack 66 and properly positioned in relation to the heel by an adjustable gage 68.

Indicating marks, such as are shown at

70, may be placed upon the periphery of the turret as an aid to the operator in determining instantly which pattern element and heel holder unit is in operative position. The rubber heels of commerce usually bear identifying numbers, and the indicating mark 70 may conveniently be the same as those upon the heel for which the corresponding pattern element and heel holder unit is designed.

The holes or openings 28 are sufficiently flared or tapered so that the guide tubes 18 automatically find their positions when the turret is elevated after it has been depressed to permit a desired pattern controlling 80 and heel holding unit to be placed in operative relation to the drivers, and the range of angular movement of the guide tubes is, or may be such that a complete, ordinary range of sizes and nailings may be covered 85 with one set of guides. In the illustrated machine, for example, provision is made for eleven different sizes and nailings without the necessity of detaching any part of the 90 machine and replacing it by another.

Having described the invention, what is claimed as new and desired to be secured by Letters Patent is:—

1. In a nailling machine, the combination of a gang of nail drivers the nail engaging ends of which are movable into a plurality of different nailling patterns, and a carrier provided with a plurality of different, nail driver controlling, pattern elements, said carrier being movable independently of the nail drivers to place any selected one of said pattern elements in cooperative relation to said drivers.

2. In a nailling machine, the combination of a gang of nail drivers the nail engaging ends of which are movable into a plurality of different nailling patterns, a corresponding gang of adjustable driver guides by which the drivers are guided into said different patterns, and a carrier provided with a plurality of different pattern elements each of said pattern elements being engageable by the gang of driver guides to locate the guides according to one nailling pattern, said carrier being movable independently of the driver guides to place any selected one of said pattern elements in position to be engaged by said driver guides.

3. In a nailling machine, the combination of a gang of nail drivers, and a rotary turret having a plurality of sets of differently arranged guide holes therethrough, said turret being movable to place any one of said sets of guide holes in guiding relation to the drivers.

4. In a heel nailling machine, the combination of a gang of nail drivers, and a carrier provided with a plurality of different, nail driver controlling, pattern elements and with an equal plurality of heel holders,

each of the heel holders being so constructed and related to a corresponding pattern element as to locate and hold a heel having nail holes arranged according to one of said pattern elements in proper relation to the respective pattern element to cause the drivers to coincide with the nail holes in

10 said heel, said carrier being movable to place any one of said pattern elements and its associated heel holder in co-operative relation to said drivers.

5 In testimony whereof I have signed my name to this specification.

ELMER R. POPE.
